UNITED STATES PATENT OFFICE.

ANTHONY NYARY, OF CHICAGO, ILLINOIS, ASSIGNOR TO PAUL H. BUSH, OF CHICAGO, ILLINOIS.

DOOR-LOCK.

1,253,416.

Specification of Letters Patent. Patented Jan. 15, 1918.

Application filed May 16, 1917. Serial No. 168,920.

To all whom it may concern:

Be it known that I, ANTHONY NYARY, a citizen of the United States, and a resident of Chicago, in the county of Cook and State 5 of Illinois, have invented certain new and useful Improvements in Door-Locks, of which the following is a specification.

My invention relates to improved locking mechanism particularly adaptable for the 10 locking of doors in commercial vehicles.

The object of my invention is to provide simple, inexpensive and efficient locking mechanism which can be readily applied to members to be locked, and which will securely hold the members in locked position and will prevent rattling of such members and of the lock parts.

On the accompanying drawings the above and other features of the invention are illustrated. In the drawings—

Figure 1 is a front view of the door lock applied to two members to be locked together,

Fig. 2 is a sectional view on plane 2—2, 25 Fig. 1,

Fig. 3 is a rear view of the locking bar,

Fig. 4 is a front view of the plate to which the locking bar is hinged,

Fig. 5 is a front view of the latch lug supporting plate,

Fig. 6 is an enlarged sectional view on plane 6—6, Fig. 2, and

Fig. 7 is a perspective view of the lock cylinder.

In Figs. 1 and 2 the parts *a* and *b* may be two hinged doors or only one of the members may be a door and the other a frame-part, and *c* represents a stop for the door or doors. On one of the parts, a plate 10 is secured as by screws 11 and has at its outer end the transverse hinge lug 12 to which one end of the locking bar *B* is pivoted by the pin 13. This locking bar is preferably formed of sheet metal comprising the top 14, the outer end flange 15, and the side flanges 16 and 17, the hinge pin 13 passing through the inner end flange of the side flanges 16 and 17. Secured to the other part *b* as by means of screws 18 is a plate 19 which has the latch lug 20 riveted or otherwise secured thereto and provided with the transverse latch notch 21 in its outer side. At the outer end of the locking bar a latch plate 22 is held against the top of the bar by pins 23 and 24 which extend transversely between

and are secured in the side flanges 16 and 17. The front end 25 of the latch plate deflects rearwardly and between this end and the end 15 of the locking bar is interposed a compression spring 26 which tends to hold the latch plate inwardly with its deflected end 25 against the pin 24. This latch plate has the rectangular hole 27 therethrough whose outer edge is of reduced thickness to form a latch tongue 28 for engaging in the latch notch 21 of the latch lug 20 when the latch plate is held inwardly by the spring 26. Rigidly secured against the outer face of the locking bar at its swinging end is a knob 29 having the cylindrical chamber 30 therein and through the top of the knob extends the key slot 31 for receiving a key *k*, the slot having the central circular enlargement 32 in which the neck *n* of the key may turn. In the chamber 30 is the cylinder 33 which has the diametral slot 34 extending longitudinally therethrough from the top to within a short distance from the bottom, this slot being adapted to register with the key slot 31 to permit insertion of the key 35 into the cylinder. Extending eccentrically from the lower end of the cylinder is the pin 35 which projects into the transversely elongated hole 36 through the latch plate so that when the cylinder is turned with the key the latch plate will be shifted forwardly against the force of spring 26 to release the latch tongue 28 from the latch notch 21. When the locking bar is swung from open position against the members *a* and *b* to be locked together, the latch tongue 28, whose lower edge is beveled, will slide past the rounded upper edge of the latch lug and the latch lug will be shifted outwardly until the tongue comes into registration with the latch notch 21 whereupon the latch plate will be shifted inwardly by the spring 26 to carry the latch tongue into the latch notch and to lock the locking bar to the plate 19 which is secured to the member *b*. To unlock the bar, the key is inserted through the key-hole into the cylinder and then when the key is turned, the cylinder will turn therewith and the pin 35 engaging in the hole 36 will swing the latch plate outwardly to release the latch tongue from the notch and the locking bar can be swung into position at perpendicular with the member *a* and the door or doors are free to be opened. It will be noted that unless the locking bar 110

is fully forced down and the latch plate moved sufficiently inwardly to permit full entrance of the latch tongue in the latch notch, the cylinder will not rotate sufficiently 5 to bring its slot 29 in coincidence with the key slot 31, and the key can then be neither inserted nor withdrawn. This insures accurate and complete locking.

The cylinders of different locks may have 10 slots of different depth or the bottoms of the slots may have different shapes so that different keys will be required to open different locks. In the construction shown, the bottom of the cylinder slot 33 has the conical 15 ridge 37 to receive the conical notch σ in the end of the key. Instead of this, the base of the cylinder may have a different shape so that only a key with a corresponding end can be inserted to operate the lock. 20 The slots of the cylinders may also be of different depth so that only keys of corresponding length can be effectively used. It is evident that more elaborate key and tumbler mechanism may be used, as for example, 25 cylinder tumbler cylinders and keys.

In order to insure tight closure of the parts a and b if these parts are doors, a leaf spring 38 is secured against the inner side of the lock bar top 14 to engage and 30 press at its ends against the plates 10 and 19 when the locking bar is closed in order to firmly press and hold the members a and b against the stop c . If the part a is a stationary frame and the part b the door, then 35 a spring may be provided for engaging only against the plate 19. Such spring will also serve to automatically swing out the locking bar when the key is turned to release the latch plate from the latch lug, and then the 40 bar can be readily grasped and swung the full distance to permit opening of the door or doors. The spring also serves to make the lock rigid when closed and to prevent rattling or vibration thereof, irrespective of 45 any wear of the latching members or looseness thereof.

The lock mechanism which I have described is of simple, inexpensive construction, yet very efficient. The locking bar body 50 14 confines and protects the latching parts whether the bar is in open or closed position, and there being a special key for each lock, opening of the lock is impossible without the right key. Although the lock may be used 55 in a great many ways it is particularly adaptable for locking the doors of commercial vehicles.

I do not, of course, desire to be limited to the exact construction, arrangement and operation disclosed as changes and modifications are no doubt possible which would still come within the scope of the invention.

I claim as follows:

1. Lock mechanism comprising a plate secured to a support, a locking bar having 65 inclosing top and side walls, said bar being hinged at one end to said plate, a plate secured to a member to be locked and having a latching lug extending therefrom to be received by the locking bar when said bar 70 is swung against the member to be locked, pins extending transversely through said locking bar, a latch plate confined in said locking bar between the top of said bar and said pins, said latching lug having a latching 75 notch and said latching plate having a latching edge, a spring tending to shift said latching plate to force the latching edge into said latching notch when the locking bar is swung against the member to be locked, 80 said latching plate having a hole, a knob rigidly secured to the locking bar over said latching plate, a lock cylinder rotatable in said knob and having a pin extending eccentrically from its lower end into said 85 latching plate hole, said knob having a key hole and said lock cylinder having a notch adapted to register with said key hole when said locking bar is locked to said lug, and a key for said lock cylinder. 90

2. Lock mechanism comprising a plate secured to a support, a locking bar having inclosing top and side walls, said bar being hinged at one end to said plate, a plate secured to a member to be locked and having 95 a latching lug extending therefrom to be received by the locking bar when said bar is swung against the member to be locked, pins extending transversely through said locking bar, a latch plate confined in 100 said locking bar between the top of said bar and said pins, said latching lug having a latching notch and said latching plate having a latching edge, a spring tending to shift said latching plate to force the latching 105 edge into said latching notch when the locking bar is swung against the member to be locked, said latching plate having a hole, a knob rigidly secured to the locking bar over said latching plate, a lock cylinder 110 rotatable in said knob and having a pin extending eccentrically from its lower end into said latching plate hole, said knob having a key hole and said lock cylinder having a notch adapted to register with said key hole 115 when said locking bar is locked to said lug, a key for said lock cylinder, and a spring within and secured to the top wall of said locking bar and adapted to engage with and press against the member to be locked when 120 said locking bar is in locked position.

In witness whereof I hereunto subscribe my name this 14th day of May, A. D. 1917.

ANTHONY NYARY.
